CLAIM

The ornamental design for a shoe, as shown and described.

DESCRIPTION

FIG. 1 is a front lateral perspective view of a shoe showing our new design;

FIG. 2 is a top view thereof;

FIG. 3 is a lateral side view thereof;

FIG. 4 is a medial side view thereof;

FIG. 5 is a rear view thereof;

FIG. 6 is a front view thereof; and,

FIG. 7 is a bottom view thereof.

In FIGS. 1-7, the lighter broken lines on the upper of the shoe, including any laces and logo, form no part of the claimed design. Also, the lighter broken lines on the outsole, including any spikes, spike receptacles and logos, form no part of the claimed design.

1 Claim, 6 Drawing Sheets
